UNITED STATES PATENT OFFICE.

DAVID C. SEARS, OF ALTUS, OKLAHOMA, AND ARTHUR M. BRADFORD, OF CLOVIS, NEW MEXICO.

BOILER-FEED MECHANISM.

Application filed November 18, 1920. Serial No. 423,788.

To all whom it may concern:

Be it known that DAVID C. SEARS and ARTHUR M. BRADFORD, citizens of the United States of America, residing at Altus, in the county of Jackson and State of Oklahoma, and Clovis, in the county of Curry and State of New Mexico, respectively, have invented new and useful Improvements in Boiler-Feed Mechanism, of which the following is a specification.

The object of the invention is to provide relatively simple automatic means for controlling the supply of water to a steam boiler to maintain an approximately uniform level therein, and incidentally to provide means for giving an alarm or signal as a notification to the attendant in the event of a failure of the automatic feeding mechanism to properly function in the supply of water to the boiler when the level falls below a predetermined plane; and with these objects in view the invention consists in the construction and combination of parts of which a preferred embodiment is shown in the drawing, wherein:

Figure 1 is a sectional view of a feed water mechanism embodying the invention.

Figure 2 is a detail enlarged section of the feed water valve.

Figure 3 is a similar view of the water column connections.

In connection with a boiler 10 there are arranged the steam and water pipes 11 and 12 provided respectively with manually operable controlling valves 13 and 14, the steam pipe being in communication with the upper end of the casing 15 of a water column and the water pipe being in communication with the lower end of said casing so as to insure under normal conditions the maintenance in the water column of a water level corresponding with that in the boiler. The water column may be provided with the usual water gauge 16, although if the water column casing is of transparent material or is provided with a transparent panel, it is obvious that the separate water gauge may be omitted. The casing of the water column is also provided with the usual gauge cocks 17, 18 and 19 while in communication with the steam pipe there may be a branch 20 leading to a steam gauge (not shown) as in the ordinary practice. The water pipe 12 is preferably branched as at 21 for communication with

the bottom of the casing of the water column and at 22 for communication with the pump indicated at 23, a suitable manually operable cut-off valve 24 being arranged in the branch 22, together with a 60 check valve 25, as ordinarily found desirable, while interposed in the branch 22, between the pump and the feed water pipe 12 is arranged a T 26 forming a casing or housing for a feed water valve 27 of which 65 the stem 28 is connected by a rod 29 with a float 30 located in the water column, to the end that when the float is depressed by the fall of water in the boiler and the casing of the column the feed valve 27 is opened to 70 permit of the passage of water from the pump to the boiler and the water column. The branch pipes 21 and 22 which are in communication with the feed water pipe 12 are preferably arranged in alignment, 75 to the end that the straight valve operating rod 29 may be employed to extend from the float to the stem of the feed water valve, as shown in the drawing, and as the valve and the rod are thus enclosed throughout 80 in the feed water conductor, they are not exposed to any friction or resistant pressure tending to obstruct the free movement thereof under the influence of the float.

Extending from the upper or steam compartment of the water column is an alarm tube 31 terminating for example in a whistle 32 and having a manually operable cut-off valve 33, a controlling valve 34 being arranged in said tube and having its 85 stem 35 provided with a rocker arm 36 connected by a link 37 with the float to the end that when the float drops below a predetermined level the valve 34 will be opened to permit the escape of steam through the 90 alarm tube to sound the whistle or other signalling device to warn the engineer or attendant that the mechanism requires attention. The link 37, however, preferably has a slot connection with the cross arm 100 36 so that the limited movement of the float sufficient to cause the opening of the feed valve 27 to allow feed water to pass to the boiler may occur without opening the whistle controlling valve 34 and thus sounding the alarm to the end that if the mechanism is functioning properly the supply of water necessary to maintain a practically uniform level in the boiler will be furnished 105 without giving the alarm. But should the 110

feed water mechanism fail to function properly the continued depression of the float will cause the actuation of the cross arm 36 and hence the opening of the alarm valve to afford a warning in time to enable the engineer or attendant to apply the necessary remedy before serious injury to the boiler or related mechanism can result by reason of the falling of the level of the water below a safe limit.

It will be noted that by the arrangement indicated a single water connection with the boiler adapted to afford communication both with the water column and with the pump is sufficient, and in addition thereto the described arrangement avoids the use of stuffing boxes or packing boxes for the connections between the float and the feed valve, with the attendant advantages in the matter of minimizing friction and resistance as above indicated.

Having described the invention, we claim:

1. A feed water system for boilers having a water column consisting of a casing enclosing a float and in communication at its upper and lower ends with the boiler by means of steam and feed water pipes of which the latter is in communication with a water supply pump, a float controlled feed water valve interposed in said feed water pipe between the boiler and the feed

water pump, and an alarm mechanism having a pressure controlling valve in communication with the upper end of the water column casing and operatively connected with the float, said valve having its stem provided with a cross arm and a link connecting the cross arm with the float.

2. A feed water system for boilers having a water column consisting of a casing enclosing a float and in communication at its upper and lower ends with the boiler by means of steam and feed water pipes of which the latter is in communication with a water supply pump, a float controlled feed water valve interposed in said feed water pipe between the boiler and the feed water pump, and an alarm mechanism having a pressure controlling valve in communication with the upper end of the water column casing and operatively connected with the float, said pressure valve having its stem provided with a cross arm, and the float having a slotted link in engagement with the cross arm for permitting a limited movement of the float independently of the cross arm.

In testimony whereof they affix their signatures.

DAVID C. SEARS.
ARTHUR M. BRADFORD.
